UNITED STATES PATENT OFFICE.

ESSINGTON N. GILFILLAN, OF CHICAGO, ILLINOIS, ASSIGNOR TO NEW YORK
LABELING MACHINE COMPANY, OF NEW YORK.

LABELING-MACHINE.

SPECIFICATION forming part of Letters Patent No. 675,887, dated June 11, 1901.

Application filed May 28, 1900. Serial No. 18,338. (No model.)

To all whom it may concern:

Be it known that I, ESSINGTON N. GILFILLAN, a citizen of the United States, residing at Chicago, in the county of Cook and State 5 of Illinois, have invented certain new and useful Improvements in Labeling-Machines, of which the following is a full, clear, and exact specification.

My invention relates more particularly to 10 machines for applying paste to the label in order that the same may be affixed to the bottle or package, and has for its primary object to provide a simple and convenient device that will apply paste over the desired area of 15 the label and hold the label in a convenient position to be pressed against the package or bottle to be labeled, thus leaving both hands of the operator free to be engaged solely in picking up the bottle or package and pressing 20 the label against it.

With these ends in view my invention consists in certain features of novelty in the construction, combination, and arrangement of parts by which the said objects and certain 25 other objects hereinafter appearing are attained, all as fully described with reference to the accompanying drawings, and more particularly pointed out in the claims.

In the said drawings, Figure 1 is a side elevation of my improved labeling-machine. Fig. 2 is an enlarged plan view thereof. Fig. 3 is a vertical section taken on the line 3 3, Fig. 2. Fig. 4 is a detail transverse section taken on the line 4 4, Fig. 2. Fig. 5 is a detail transverse section taken on the line 5 5, Fig. 2; and Fig. 6 is a perspective view of a dog or pawl hereinafter described.

1 represents any suitable frame or stand for supporting the operating mechanism at a 40 convenient height from the floor, and between the side members 1^a of the upper portion of this frame is supported a cross-bar 2, in which is formed a number of vertical sockets or guides 3 for the reception of downwardly-extending stems 4, formed on the bottom of a label-bed 5, which is thus made vertically movable and which supports a box 6, containing the labels 7, the box being provided with a number of pins 8, engaging in sockets 50 or perforations 9 in the bed 5, so as to hold the box in place with capability of being removed when it is desired to refill it or to in-

sert a box of labels of a different size. The label-box 6 consists of a flat plate having tongues 6^a turned upwardly therefrom at the 55 ends and corners to hold the labels in place, while at the same time permitting label pasting and carrying fingers 10 to come into contact with the surface of the uppermost label. These fingers 10 are arranged in a horizontal 60 position and preferably parallel with each other, so as to come in contact with remote edges of the label, and each is provided with a rubber or other suitable surface 11, appropriate for carrying paste and applying the 65 same to the label. The label pasting and conveying fingers 10 are reciprocated in a horizontal direction, so as to pass successively over paste-rollers 12 13 and the label-bed and to pick up a label from the latter and project 70 it forward over and beyond the rollers 12 13, so as to be in position to have the bottle or package inserted downwardly between the fingers 10 for causing the label adhering thereto to stick to the bottle, the bottle being held in one hand 75 and the other hand being placed below the label as it adheres to the fingers 10 and pressed against the bottle and smoothed out as the bottle descends. Each of the fingers 10 is provided with an arm 14, which has a pivot 80 pin or shaft 15, mounted in ears 16, rising from a plate 17, which is mounted on a sliding frame 18, having lugs 19, sliding on parallel guide-rods 20, supported on opposite sides of the frame in brackets 21. The plates 85 17 are also mounted with capability of sliding transversely of the line of movement of the sliding frame 18, and they are each provided with a set-screw 22, which passes downwardly through a slot 23 in the frame 18, so 90 that the fingers 10 may be set at various distances apart for use with labels of different sizes. In order that a small label may be applied to a bottle or package too large to be passed between the fingers 10, such fingers 95 are made laterally deflectable, or, in other words, turn on their pivot-shafts 15 in an outward direction to permit the bottle or package to pass between them. They are returned to their normal position by means of coil-springs 24, wound on shafts 15, and their inward movement is limited by stops 25, formed on one of the ears 16, in which the shaft 15 is pivoted.

The frame 18, with its perforated lugs or slides 19, which constitutes a carriage for the fingers 10, is attached to one end of a spring 26 by means of a screw 27, which passes upwardly through a slot 28 in a cross-bar 29, to which the other end of the spring 26 is connected by means of screw 30, the cross-bar 29 lying over the frame 18 and having a lug 31 projecting downwardly through a slot 32 in 5 the frame 18 into the path of one end or arm 33 of a bell-crank lever, pivoted at 34 to the side members of the main frame, and having its other arm 35 projecting into an aperture 36, formed in the upper edge of the cross-bar 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

which is pivoted at 47 to the side members of the main frame and supports one end of a paste-trough 48, in which the paste-rollers 70 12 13 are mounted, 49 being a stop to limit the downward movement of the trough. The other end of the trough 48 is supported by pivoted arm 46^a on the opposite side of the machine. This engagement of the pawl 45 75 by the moving frame 18 throws the roller 12 up into engagement with the lower faces of the fingers 10 and supplies the latter with paste as they proceed on their return movement, the paste-rollers being thus held in 80 their elevated position as long as the pawl 45 is in engagement with the under side of the frame 18, and as soon as the frame 18 passes the pawl the paste trough and rollers gravitate to their normal position out of the way 85 of the fingers 10, so that as soon as the pressure of the operator's foot against the treadle 41 is relieved the spring 37 will project the fingers 10 forwardly again; but in making this return movement the frame 18 deflects 90 the pawl 45 upon their pivot and passes over it without depressing the arms 46, the pawl 45 being constructed, as shown in Fig. 6, with a lug 45^a on its lower end, adapted to engage with the underside of the arm 46 when pushed 95 in one direction, and thus depress the arm, but when pushed in the other direction to turn upwardly on its pivot. In making the forward movement under the influence of the spring 37 the motion of the cross-bar 29 is imparted to the carriage or frame 18 by the lug or boss 27^a, in which the screw 27 is threaded, the boss being projected upwardly in the slot 28, and in making its return movement the motion of the cross-bar 29 is imparted to the 100 frame 18 through the medium of the spring 26 until the bosses or slides 19 come against the brackets 21, whereupon the spring 26 permits the cross-bar 29 to slide still farther to the rear and bring the lug 31 against the arm 105 33 for lifting the labels. The cross-bar 29 is provided with a narrowed portion 29^a at its rear side, guided between two flanges 50, formed on the upper side of the frame 18. If desired, the rear side or edge of the frame 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

As the carriage 18 and fingers 10 return to the position shown in Fig. 3 a toothed bar 52, secured at 53 to the under side of the frame 120 or carriage 18 and held in a horizontal position, comes into engagement with a ratchet-wheel 54 on the paste-roller 12, and thus rotates the roller while the fingers 10 are passing over it.

Having thus described my invention, what I claim as new therein, and desire to secure by Letters Patent, is—

1. A labeling-machine having in combination a vertically-movable label-holder, a vertically-movable paste-supplying device, reciprocating paste-applying fingers, levers oscillating in unison with the movement of said fingers for lifting said label-holder and paste 130

device respectively, and means for reciprocating said fingers, substantially as set forth.

2. A labeling-machine having in combination a vertically-movable label-holder, a reciprocating carriage, paste applying and carrying fingers mounted on said carriage, a vertically-movable paste apparatus, pivoted arms or levers for lifting said paste apparatus and label-holder respectively, a yielding projection on said carriage for engaging the lever which raises said label-holder and means on the lever which raises the paste apparatus, adapted to engage the carriage when moving in one direction but permit it to pass when moving in the opposite direction, substantially as set forth.

3. A labeling-machine having in combination a vertically-movable label-holder, a vertically-movable paste apparatus, means for imparting a vertical movement thereto, a sliding carriage, fingers carried by said carriage for alternately engaging said paste apparatus and label-holder, a lever for lifting said label-holder, a cross-bar connected with said carriage by a yielding connection and having a lug projecting into engagement with said lever and having limited independent movement and means for reciprocating said cross-bar, substantially as set forth.

30 4. A labeling-machine having in combina-

tion a label-holder, reciprocating label pasting and carrying fingers, means for causing the labels on said holder and said fingers to come into contact, a movable paste apparatus adapted to approach the line of movement of said fingers, a pivoted arm for moving said paste apparatus, a pivoted pawl on said arm adapted to be struck by a part connected with said fingers for deflecting said arm when moving in one direction and to deflect said pawl 35 and pass over said arm when moving in the opposite direction and means for reciprocating said fingers, substantially as set forth.

5. A labeling-machine having in combination a reciprocating carriage, a label-holder, 40 label pasting and applying fingers carried by said carriage, means for causing the labels on said holder and fingers to come into engagement, a movable paste apparatus having a roller, a ratchet on said roller, a rack-bar carried by said carriage over said ratchet and means for moving said paste apparatus with said roller against said fingers and said ratchet against said rack-bar as the carriage reciprocates, substantially as set forth.

E. N. GILFILLAN.
